UNITED STATES PATENT OFFICE

2,569,037

RELEASABLE LOCK FOR ELECTRIC PLUGS

John J. Dalton, Lakewood, N. Y.

Application December 22, 1949, Serial No. 134,380

2 Claims. (Cl. 173—330)

1

This invention relates to a releasable locking device for electric plug connectors, and more particularly to a locking device engageable on the escutcheon plate of duplex electric outlets for releasably securing a single plug, two plugs of equal length, simultaneously, or two plugs of unequal length simultaneously in full contact engagement with the outlet.

It is an object of this invention to provide a locking device of the kind to be more particularly described hereinafter which is inconspicuous, simple in structure, economical in cost and easy of installation, for attachment to the face of an escutcheon plate of a duplex electric outlet and engageable with a plug or plugs engaged in the outlet in such a manner as to prevent the inadvertent detachment of the plug or plugs, as by children or by the exerting of undue strain on the appliance cord, and yet providing for the ready and speedy removal of the plug or plugs when and as desired.

Another object of this invention is to provide a device of this kind formed of a minimum number of essential parts of substantially conventional structure or so fashioned to be formed by conventional machine shop equipment and procedure, the parts being inexpensive yet capable of extended hard use without repair or replacement.

A further object of this invention is to provide an electric plug locking means of this kind for positively securing the plug or plugs in the outlet against accidental separation therefrom and against partial separation or short circuits resulting from partial separation of the plug or plugs from the outlet.

With the above and other objects in view, my invention consists in the arrangement, combination and details of construction disclosed in the drawings and specification wherein like reference characters designate like parts throughout the several views, and then more particularly pointed out in the appended claims.

In the drawings:

Figure 1 is a side elevation of a plug locking device, constructed according to an embodiment of my invention, engaged in a duplex electric outlet, having a cover or escutcheon plate and simultaneously locking two plugs of equal length in contact position in the outlet, the escutcheon plate being shown in longitudinal section;

Figure 2 is a front elevation;

Figure 3 is a perspective view of the locking post element removed from the assembly of the device;

Figure 4 is a perspective view of the retaining bolt removed from the assembly of the device;

Figure 5 is a perspective view of the top of one of the locking plates or yokes removed from the assembly;

Figure 6 is a perspective view of the bottom of one of the locking plates or yokes removed from the assembly;

Figure 7 is a side elevation of the plug locking device as applied when locking two plugs of different lengths;

Figure 8 is a side elevation showing the locking post in position as protective shield over the retaining bolt when no plugs are being used in the duplex outlet;

Figure 9 is a longitudinal section through the locking post removed from the assembly.

Referring to the drawings wherein like reference characters designate like parts throughout the several views, the numeral 10 designates generally a locking device constructed according to an embodiment of my invention for releasably securing an electrical appliance cord plug to an escutcheon plate 12 over a conventional style and type of duplex electric outlet 14. The locking device 10 is adapted to simultaneously lock twin plugs of the same length, to simultaneously lock two plugs of different lengths, or to lock a single plug on escutcheon plates having two outlet openings as generally used in wiring circuits of homes, offices, commercial buildings, etc.

The locking device 10 is formed with a central screw member 15 adapted for connection in the central aperture 16 of the escutcheon plate 12 in place of the usual countersunk screw, not shown in the drawings. The screw member 15 is formed with an integral, reduced diameter, threaded mounting screw end or portion 17 adapted to be slidably engaged through the mounting hole or countersunk aperture 16 of the escutcheon plate 12 and threadably engaged with the nut element or member 18 of the outlet base 19 fixedly mounted in the wall or other supporting structure and on which the sockets 14 are mounted.

The other portion of the screw member 15 is formed with an integral screw 20 equipped with a screw driver slot and having an outside diameter greater than the outside diameter of the mounting screw end or portion 17, for use in a manner to be more particularly described hereinafter. The inner end of base screw 20 is joined to the outer end of the mounting screw 17 by a tapered shoulder 21. The tapered shoulder 21 is adapted to be seated in the marginal depression of the aperture 16 or countersunk face of the escutcheon plate 12 for limiting the threaded engagement of the mounting screw element 17 in the supporting nut element 18. By limiting the inward extension

of the screw member 15 through the escutcheon plate 12, the base screw 20 is supported totally on the outer face of the escutcheon plate, as clearly noted in Figure 1 of the drawings.

A locking post 22 is threadably mounted on the base screw 20 for threaded adjustment along the length thereof. The thumb nut or locking post 22 is formed of a nonconducting, substantially cylindrical body 24 having a central, threaded bore 25 for engagement with the screw element 20. The body 25 is preferably undercut or formed to provide a plurality of longitudinally spaced apart, circular plates or discs 26 along the length thereof. The locking member or post 22 is adapted to be engaged on the base screw member 20 between adjacent male plug connectors 11 engaged in sockets 14.

A pair of locking yokes 28 and 29 are formed for releasable engagement with locking post 22 and an adjacent electric cord 27 where cord 27 emerges outwardly from male connector plug 11 carried by the respective cord. Each of the yokes 28 and 29 is formed of a flat plate 30 of nonconducting or insulating material formed with a laterally offset face 31 at one end. The yokes 28 and 29 are distinguished from each other only by the structure wherein one of the plates has a rearwardly offset face 31 extending laterally from the front face of the plate a distance different from the offset of rearwardly offset face of the other yoke member. By such relative configuration, the front faces of the yokes 28 and 29 may be offset from each other on the mounting post 22, as noted in Figure 1 of the drawings, and the rearwardly offset faces of the yokes may lie in the same plane for engaging the outer ends of similar length plugs 11 engaged in sockets 14 covered by escutcheon plate 12. At such times when adjacent plugs, as plugs 11A and 11B, noted in Figure 7 of the drawings, are engaged in the sockets covered by plate 12, and these plugs are of different lengths and/or configurations, the yokes may be positioned on the post 22 to suit the particular plug with which it is to be lockingly engaged.

The yokes, both yoke 28 and yoke 29, are formed with a pair of U-shaped notches 32 and 34 opening on one side edge. One notch, as the notch 32, is positioned transversely of the plate at one end, the flat end, while the other slot 34 is inclined at an angle to the longitudinal axis of the plate at the other or offset end and opens adjacent the transverse median of the plate. The transverse slot 32 of each plate or yoke is adapted to be slidably positioned between a pair of adjacent disc plates 26 on the locking post 22 for sliding and rotating engagement on the post at a selected position. The inclined slot 34 is adapted to receive the cord 27 of an electric appliance or the like for securing the plugs 11 engaged by the prongs thereof in the socket 14 against inadvertent removal from the socket, the offset face of the yoke being spaced from the escutcheon plate 12 a selected distance very close to the depth or length of the plug 11. In the case of the plugs being of different lengths, one or both yokes may be reversed in their engagement between the disc plates 26 on the locking post 22, so that the flat side of one, or both yokes, is spaced from the escutcheon plate 12 a selected distance very close

to the depth or length of the plug, this multiplicity of arrangements of the yokes between the disc plates 26 permits of a wide range of spacings between the yoke face and the escutcheon plate.

With a plug 11 engaged between a yoke 28 or 29 and the escutcheon plate 12, the yoke or yokes may be securely clamped to the plug 11 by rotating the locking post 22 inwardly along the length of base screw 20. For separating the plug 11 from the socket 14, it is necessary only to rotate post element 22 outwardly along the length of base screw 20 and slide the yoke transversely of the mounting post, as noted by the broken lines in Figure 2 of the drawings.

I do not mean to confine myself to the exact details of construction herein disclosed, but claim all variations falling within the purview of the appended claims.

I claim:

1. A releasable locking device for removably securing an electric plug to a related socket comprising a locking post, a plurality of spaced apart coaxial discs on said post, means securing said post on an escutcheon plate in adjusted spaced relation therefrom, a pair of locking plates slidably and rotatably engageable on said post, each of said locking plates having a laterally opening notch for slidably engaging said post between a pair of adjacent discs, at least one of said locking plates having an offset end for disposition in the same transverse plane as the other locking plate when engaged between another pair of discs on said post, the outer ends of each of said locking plates having an open-sided notch for slidably receiving an electric cord having a plug thereon for clampingly securing the plug between the respective locking plates and the escutcheon plate.

2. A releasable locking device for removably securing an electric plug including a cord to an outlet socket in an electric wall fixture comprising a locking post adapted to be arranged transversely of said fixture and having one end adapted to be fixedly secured to said fixture adjacent said socket, a plurality of spaced apart discs fixedly positioned along said post inwardly of the other end thereof, a locking plate positioned transversely of said post and having a notch extending inwardly of one side edge adjacent one end thereof slidably and rotatably embracing any selected portion of said post intermediate adjacent discs, and means embodying a second notch formed in said locking plate and extending inwardly of one side edge of said plate adjacent the other end for embracingly engaging the portion of the cord adjacent the electric plug and bearing against the adjacent end of said plug when the latter is inserted in said socket.

JOHN J. DALTON.
